UNITED STATES PATENT OFFICE

90,847

DESIGN FOR A SIGN

Donald C. Hansen, Geneva, Ohio, assignor to Erie
Shores Ice Cream Company, Geneva, Ohio

Application July 12, 1933. Serial No. 48,702

Term of patent 3½ years

To all whom it may concern:

Be it known that I, DONALD C. HANSEN, a citizen of the United States, residing at Geneva, in the county of Ashtabula and State of Ohio, have invented a new, original, and ornamental Design for a Sign, of which the following is a specification, reference being had to the accompanying drawing, forming part thereof, and in which:

The figure is a perspective view of the sign.

I claim:

The ornamental design for a sign, as shown.

DONALD C. HANSEN.
